(57) **CLAIM**

The ornamental design for modular laboratory cabinet, as shown and described.

DESCRIPTION

FIG. 1 is a perspective view of one embodiment of the modular laboratory cabinet according to our new design; FIG. 2 is a perspective view of another embodiment of the invention, the sole difference residing in the color coordination that is shown; FIG. 3 is a front elevational view thereof; FIG. 4 is a rear elevational view thereof; FIG. 5 is a top plan view thereof; (a bottom plan view is a mirror image of FIG. 5); FIG. 6 is a left-hand side elevational view thereof; FIG. 7 is a right-hand side elevational view thereof; FIG. 8 is a front elevational view of another embodiment of the invention having two modular units; FIG. 9 is a rear elevational view thereof; FIG. 10 is a top plan view thereof; FIG. 11 is a bottom plan view thereof; FIG. 12 is a left-hand side elevational view thereof; FIG. 13 is a right-hand side elevational view thereof; FIG. 14 is a front elevational view of a further embodiment of the invention having three modular units; FIG. 15 is a rear elevational view thereof; FIG. 16 is a top plan view thereof; (a bottom plan view is a mirror image of FIG. 16); FIG. 17 is a left-hand side elevational view thereof; FIG. 18 is a right-hand side elevational view thereof; FIG. 19 is a front elevational view showing still another embodiment of the invention having four modular units; FIG. 20 is a rear elevational view thereof; FIG. 21 is a top plan view thereof; (a bottom plan view thereof is a mirror image of the view shown in FIG. 21); FIG. 22 is a left-hand side elevational view thereof; and, FIG. 23 is a right-hand side elevational view thereof.

The broken lines shown are for illustrative purposes only and form no part of the claimed design.
